ARTHUR E. BROUGHTON, OF MINNEAPOLIS, MINNESOTA

CONDENSATE-REMOVAL DEVICE FOR HIGH-SPEED PAPER DRIERS

Application filed April 23, 1928. Serial No. 272,166.

Heretofore where paper driers have been operated at peripheral speeds of more than 800 feet per minute the removal of the condensate has been intermittent and this has 5 made it necessary to frequently change the pressure at which the steam is supplied to the driers. Even where rapid and frequent changes in the pressure are made it has not been possible in the old systems to 10 secure uniform drying of the sheet. This lack of uniformity in the drying has led to the practice of removing more than the requisite amount of moisture from some parts of the sheet with consequent losses 15 to the manufacturer. In the old systems the intake opening in the withdrawal pipe has been located at a point closely adjacent to the lower periphery of the drier but this does not effect a continuous withdrawal be- 20 cause when the higher speeds are attained a relatively large amount of condensate is carried around with the drier by centrifugal force and is retained in a film or layer ex- 25 tending upon the entire inner periphery of the drier. Periodically, when the condensate has collected in such a large amount that it can no longer be so carried around, it suddenly falls and is drawn out of the drier rapidly for the short period of time re- 30 quired to reduce the quantity remaining in the drier to a point where it is again spread upon the entire periphery. This periodical withdrawal of large amounts of the condensate is what is known as "slugging" 35 and causes the detrimental variations in the rate of drying.

It is my object to eliminate such slugging and the necessity for over drying and rapid changes in the steam pressure by providing 40 efficient means for substantially continuously removing condensate from high speed driers. Other objects will appear and be more fully pointed out in the following specification and claims.

45 I have found by experiment that with a given cylindrical drier containing a fixed small amount of water that this water will remain in a relatively stationary body in the bottom when the drier is rotated at peripheral speeds below about 800 feet per minute. 50

As the speed of this drier is increased the water tends more and more to follow around the periphery and when another somewhat higher speed is reached it is carried partially around and then falls transversely of 55 the axis of the drier. At a still higher speed with the same drier containing the same amount of water the entire body of water will adhere to the periphery and spread over the entire peripheral surface of 60 the drier in a relatively thin layer or film. Conversely when a drier is operated at any substantially uniform speed above about 800 feet per minute there is a corresponding 65 small quantity of water which will spread upon the periphery and rotate with the drier, a somewhat larger amount which will be carried partially around the periphery and a still larger amount which will be re- 70 tained in a stationary body in the bottom. 75 Of course, it is undesirable to form an insulating film of water upon the inner periphery of the drier. Therefore it is ad- 80 vantageous to retain sufficient water in the drier so that it will not be carried com- pletely around by the centrifugal force. On the other hand, it is best to remove as 85 much as possible down to the limit thus es- tablished.

By the present invention I maintain a 80 balance between the two extremes by pro- viding one element adapted to prevent the removal of an excessive amount and another element adapted to remove a maximum 85 which it is possible to remove above the point where the water will spread upon the periphery of the drier. I provide a recep- 90 tacle located in such position that it will collect and remove a substantial part of the water which falls transverse the axis of the 95 drier. An intake opening in a withdrawal pipe is located at a point sufficiently far above the lower periphery of the drier to retain a predetermined minimum of water (depending on the speed of the particular drier) which is large enough so that it will not be carried in a film covering the inner periphery. Thus in the normal operation 100 of the driers at a predetermined high speed I retain the water therein at the critical

point where the excess continuously falls transverse the axis and is caught in a receptacle from which it is removed.

In the accompanying drawings Figure 1 is a longitudinal, vertical section through a drier of common type with my improved condensate removal device attached thereto, together with suitable means for admitting steam and for rotating the drier; Fig. 2 is an enlarged transverse section through the drier and present invention taken on the line 2—2 of Fig. 1; Fig. 3 is an enlarged fragmentary, longitudinal section through an end of the device and drier and Fig. 4 is a section of the U-shaped part of the withdrawal pipe and adjacent connections.

In the drawings the numeral 5 indicates a cylindrical drier of the common type mounted with its axis substantially horizontal and supported for rotation in suitable bearings 6 and 7. Fixed on one end of the drier is an axial shaft 8 which projects through the bearing 7 and is provided with a driving gear 9 of common type. The shaft 8 is hollow, being provided with a passageway communicating with the interior of the drier 5 through an opening 10. A condensate removal pipe 11 extends axially through the shaft 8 and opening 10. At its outer end the pipe 11 is secured to a stationary fitting 12. From this fitting it passes through a hollow head 13 communicating with a steam supply pipe 14.

Projecting axially into the drier 5, the pipe 11 has a central bearing 15 in a spider 16, said spider being bolted to the end of the drier so as to rotate around the stationary pipe 11. Beyond the bearing 15 the pipe 11 communicates with a T coupling 17 which in turn connects with one end of a U-shaped pipe 18. The lower extremity of this U pipe is located near the inner periphery of the drier and one of its branches communicates through a T coupling 19 with an axially positioned pipe 20. Openings 21 in the upper periphery of the pipe 20 admit condensate thereto from a receptacle 22 which extends longitudinally within the drier and projects laterally from the central part thereof. This receptacle 22, as best shown in Fig. 2 is supported upon the pipe 20 and arranged to drain into said pipe. As shown in Fig. 3 the pipe 20 is closed at its end remote from the U pipe 18 and is supported by a spider 23 similar to the spider 16, a suitable journal bearing 24 being provided between the pipe and spider to permit rotation of the spider with the drier, the pipe 20 being stationary.

It will be noted, as shown in Fig. 4, that a threaded plug 24 is arranged to close adjacent branches of the couplings 17 and 19 while an intake opening 26 is located in the upper periphery of the U pipe 18 near its lower extremity. Thus the pipe 20 com-

municates through the U pipe 18 with the pipe 11 and is arranged to empty by gravity into the U pipe. Suitable unions 27 are provided to facilitate making the connection of the U pipe 18 to the couplings 17 and 19.

Any suitable or well known means may be provided for forcing or withdrawing the condensate out through the pipe 11. As illustrated, such means are of the type shown in my Patent No. 1,575,615 dated March 9th, 1926, for heating systems for paper driers. Thus a pipe 28 is arranged to communicate at one end with the condensate header 29 and at its other end with the pipe 11. A check valve 30 is located in the pipe 28 to permit flow of condensate from the drier into the header 29 while preventing flow of steam in the reverse direction. The steam supply pipe 14 is connected to the steam header 31 of the paper drier in a suitable manner.

Operation

In operation I prefer to locate the U-shaped pipe 18 at an acute angle, about 15°, in advance of its vertical position as indicated in Fig. 2 so that it projects into the deepest part of the condensate 32. As will be readily understood the condensate is deepest in the higher speed driers at a point removed in the direction of rotation from the lowest point of the inner periphery. The arrow in Fig. 2 indicates the direction of rotation. The height of the U pipe 18 is such that with a given speed the opening 26 will be located far enough from the inner periphery so that it cannot reduce the quantity of condensate to such a degree that it carries around with the drier.

When starting a high speed paper drier it is operated at a speed considerably below the normal and during this period of low speed operation the U pipe 18 operates to withdraw the condensate into the opening 26 as fast as it is formed. Thus as soon as the opening 26 is covered by condensate, steam in the pipes 11 and 28 and in one arm of the pipe 18 condenses and creates a partial vacuum which draws the condensate into the pipe 28 whence it flows by gravity past the check valve 30 into the header 29.

When the speed of the drier is increased to its normal operating speed above 800 feet per minute, the condensate within the drier tends to follow around the periphery of the drier until it reaches a point where some of it falls transverse the axis of the drier as shown at 33 in Fig. 2. A substantial part of the water thus caused to fall is caught in the receptacle 22 whence it flows into the pipes 20 and 18 and is drawn out as above described. In this manner a sufficient quantity is continuously removed to prevent an objectionably large amount from accumulating. Only as long as the water is falling from the upper periphery of the drier is it withdrawn by the

receptacle 22, so that neither too little nor too large a quantity is removed. If the condensate tends to accumulate in a quantity so great that it is not delivered to the receptacle 22 it will fall to the bottom and be drawn out through the opening 26 in the pipe 18 which is located at such a point that it can not reduce the level below that required to supply the receptacle 22 at the predetermined operating speed.

In this manner, and with proper adjustment of the location of the opening 26, the condensate is continuously withdrawn both at the lower starting speeds and at the normal operating speed of the drier. I have found that with a high speed drier, 4 feet 8 inches in inside diameter and normally operating at a peripheral speed of about 900 feet per minute the opening 26 should be about 2 $\frac{1}{4}$ inches from the nearest point on the inner periphery of the drier. It will be readily understood that the spacing of the opening 26 from the periphery of the drier is greater for higher operating speeds and smaller for lower speeds to insure retention of the critical minimum quantity of condensate within the drier.

Where a peripheral speed of 900 to 1,000 feet per minute is required, the spacing of the opening 26 from the lowest point on the inner periphery of the drier is made about two and one-half inches so as to retain, when the drier is stationary, water at a depth of about two and one-half inches in the bottom of the drier. For a peripheral speed of 1,200 feet per minute about three inches of water should be retained in the bottom when the drier is stationary, while an amount represented by a depth of from three to four inches is required for a peripheral speed of 1,400 feet per minute on the same drier of four feet eight inches internal diameter. These are the high speeds which are now required. It will be evident that where the peripheral speed of the drier is known in advance, the pipe 18 may be designed to retain the opening 26 at the desired distance from the bottom, but where it is desired to change the speed from time to time adjustment of the height of the opening 26 may be made by merely changing the angle of the pipe 18 relative to the vertical plane through the axis of the drier.

Having described my invention what I claim is new and desire to protect by Letters Patent is:

1. In a condensate removal device for a high speed cylindrical drier, a condensate removal pipe having an intake opening spaced from the lower periphery of said drier to retain a predetermined minimum of condensate within the drier which is in excess of that which will adhere to the entire periphery of said drier when the same is operated at a predetermined high speed and

a receptacle arranged to continuously remove condensate in excess of a predetermined amount when said drier is operated at the same high speed.

2. In a condensate removal device for a high speed cylindrical drier, a condensate removal pipe having an intake opening spaced from the lower periphery of said drier to retain a predetermined minimum of condensate within the drier, said minimum exceeding the quantity which normally spreads upon the periphery when the same is operated at a predetermined, normal high speed, a receptacle for condensate arranged to continuously collect quantities of condensate in excess of a predetermined amount, and connections for removing condensate from said pipe and receptacle.

3. In a condensate removal device for a high speed cylindrical drier, a condensate removal pipe having an intake opening spaced from the lower periphery of said drier to maintain a predetermined minimum of condensate within the drier, said minimum being in excess of the quantity which will adhere to the entire periphery of said drier when the same is operated at a predetermined high speed and a receptacle arranged to collect quantities of condensate falling from the upper periphery of said drier.

4. In a condensate removal device for a hollow cylindrical drier mounted with its axis in substantially horizontal position, a normally stationary receptacle extending longitudinally in said drier and projecting laterally from the central part of the same to collect condensate falling transverse the axis thereof, said receptacle being spaced from the periphery of the drier to receive condensate removed from the periphery by gravity and connections for removing condensate from said receptacle, arranged to retain at least a sufficient body of condensate to cause dropping of the condensate from the upper periphery of the drier.

5. In a condensate removal device for a hollow cylindrical drier mounted with its axis in substantially horizontal position, a normally stationary conduit extending axially into said drier and having an intake opening adjacent to the lower periphery of said drier, a normally stationary receptacle extending longitudinally in said drier and projecting laterally from the central part of the same to collect condensate falling from the upper periphery thereof, said receptacle being spaced from the periphery of the drier to receive condensate removed from the periphery by gravity and connections for removing condensate from said receptacle and conduit, arranged to retain at least a sufficient body of condensate to cause dropping of the condensate from the upper periphery of the drier.

6. In a condensate removal device for a hollow cylindrical drier mounted with its axis in substantially horizontal position, a normally stationary conduit extending axially into one end of said drier, a normally stationary drain pipe extending axially within said drier, a receptacle extending longitudinally in said drier and projecting laterally from said drain pipe near the axis thereof and spaced a substantial distance from the periphery thereof to collect condensate falling freely within the drier, said drain pipe having openings to receive condensate from said receptacle and a connection for removing condensate from said drain pipe through said conduit, arranged to retain at least a sufficient body of condensate to cause dropping of the condensate from the upper periphery of the drier.
7. In a condensate removal device for a hollow cylindrical drier mounted with its axis in substantially horizontal position, a normally stationary conduit extending axially into one end of said drier, a downwardly projecting pipe communicating with said conduit and having an intake opening adjacent to the lower periphery of said drier, a normally stationary drain pipe extending axially within said drier, a journal bearing for said drain pipe supported on the end of said drier opposite said conduit, a receptacle extending longitudinally in said drier and projecting laterally from said drain pipe to collect condensate falling within the drier, said drain pipe having openings to receive condensate from said receptacle and a connection for removing condensate from said drain pipe.
8. In a condensate removal device for a hollow cylindrical drier mounted with its axis in substantially horizontal position, a normally stationary conduit extending axially into one end of said drier, a downwardly projecting, U-shaped pipe communicating with said conduit at one end and having an intake opening adjacent to the lower periphery of said drier, a normally stationary drain pipe extending axially within said drier and communicating with said conduit through said U-shaped pipe and a receptacle extending longitudinally in said drier and projecting laterally from said drain pipe to collect condensate falling within the drier, said drain pipe having openings to receive condensate from said receptacle.

In testimony whereof, I have hereunto signed my name to this specification.

ARTHUR E. BROUGHTON.
